[57] CLAIM

The ornamental design for a pen, as shown and described.

DESCRIPTION

FIG. 1 is a rear elevational view of a pen showing my new design;

FIG. 2 is a right side elevational view, the left side being a mirror image thereof;

FIG. 3 is a front elevational view thereof;

FIG. 4 is a top plan view thereof; and,

FIG. 5 is a bottom plan view thereof.

FIGS. 4 and 5 have been drawn to an enlarged scale with respect to FIGS. 1 through 3.

FIG. 4

FIG. 5

FIG. 3

FIG. 2

FIG. 1
